UNITED STATES PATENT OFFICE.

THOMAS MYHRUM, OF CHICAGO, ILLINOIS, ASSIGNOR TO CONTINENTAL CAN COMPANY, INC., OF SYRACUSE, NEW YORK, A CORPORATION OF NEW YORK.

SHEET-FEEDING MECHANISM.

Application filed March 1, 1920. Serial No. 362,615.

To all whom it may concern:

Be it known that I, THOMAS MYHRUM, a citizen of the United States, residing at Chicago, in the county of Cook, State of Illinois, have invented certain new and useful Improvements in Sheet-Feeding Mechanisms, of which the following is a description, reference being had to the accompanying drawing and to the figures of reference 10 marked thereon.

The invention relates to new and useful improvements in sheet feeding mechanisms, and more particularly to a sheet feeding mechanism wherein a sheet is separated 15 from a stack and is then moved edgewise into the machine operating thereon.

Prior to my invention, suction devices such as metal cups have been used for separating a sheet of metal from a stack of 20 sheets, and means has been provided for moving the sheet edgewise while held by the suction cups. It has been found in practice, however, that if a sheet is bent or ribbed or very uneven, the metal suction 25 cup will not make an air-tight engagement therewith, and the sheet will not be picked up. It is well known that rubber suction cups will lift the sheet from the stack, but so far as I am aware, it is impractical to 30 move the sheet edgewise while held by the rubber suction cup.

The object of the present invention is to provide means which may be associated 35 with yielding suction cups for lifting metal sheets from a stack, which means engages the sheet and holds the same suspended after the suction cup has released the same, and which means is so constructed that the sheet may be moved edgewise on said sus- 40 taining means into the machine which is to operate upon the sheet.

In the drawings which show by way of illustration, one embodiment of the invention:-

45 Figure 1 is an end view of a punching machine having my improved feeding mechanism applied thereto;

Fig. 2 is a view, more or less diagrammatic, on the line 2-2 of Fig. 1;

50 Fig. 3 is a sectional view on the line 3-3 of Fig. 2;

Fig. 4 is a sectional view on the line 4-4 of Fig. 3;

55 Fig. 5 is a sectional view on the line 5-5 of Figures 4 and 6;

Fig. 6 is a sectional view on the line 6-6 of Fig. 5;

Fig. 7 is a sectional view on the line 7-7 of Fig. 2;

Fig. 8 is a view showing more or less 60 diagrammatically the stack holder, the means for separating the sheets from the stack, the sustaining means and the means for feeding the sheet endwise, the suction means being in contact with the sheet for 65 lifting the same; and

Fig. 9 is a similar view but showing the sheets sustained by the magnets preparatory to the movement of the same edgewise into the machine which operates upon the 70 same.

While the invention is directed broadly to a sheet feeding means, it is particularly directed to feeding devices for removing metal sheets, one at a time, from the stack 75 holder and for feeding the sheets after being separated from the stack holder edgewise into the machine which operates upon the sheets. In the present embodiment of the invention, the machine operating upon 80 the sheets is shown as a die punching press. The machine illustrated in Fig. 1 is substantially the same character of machine as that shown and described in the patent granted to Charles D. McDonald, dated 85 March 7, 1905, Number 784,415. Said machine includes a supporting base 1 having standards 2 in which a main shaft 3 rotates. This main shaft operates the punching die and also the feeding mechanism 90 which feeds the sheets, step by step, through the machine. The sheets are directed to the feeding mechanism by means of guiding plates 4 and 5.

Mounted on the standards 2 is a stack holder 6, in which is placed a stack of metal blanks or sheets 7. The sheets are lifted, one at a time, from the stack holder, by a reciprocating plunger 8 carrying a cross head 9, and the sheets are fed into the receiving mouth between the guide plates 4 and 5 by feed fingers 10 carried by reciprocating rods 11. These rods are reciprocated by means of a link 12 connected to a lever 13 which is operated from the main shaft, 100 and the plunger 8 is also connected to a lever 14 operated from the main shaft. The parts so far described are substantially the same as those shown in the patent above referred to.

Prior to my invention, metal cups were mounted upon a cross head and connected to a suitable suction creating means which operated to place the cups under vacuum after the same had been pressed against the sheet. It has been found in practice, as above noted, that if the sheet is slightly bent, or the surface is irregular for any reason, the metal lip of the cup would not make contact with the sheet all the way around, and as a result, air would be admitted underneath the lip of the cup and the cup would therefore fail to be put under vacuum and lift the sheet from the stack. The present invention contemplates the use of rubber suction cups, which, as well known, will lift the sheet even though the surface is irregular or bent for the reason that the flexible lip of the rubber cup will conform to any irregularity in the surface of the sheet, thus making an airtight contact with the sheet so that the cup may be placed under vacuum and the sheet lifted. It is also well known that the sheets cannot be slid edgewise while suspended by rubber suction cups, and therefore the invention contemplates the use of magnets which are so associated with the flexible suction cups that the sheet will be transferred by the suction cups to the magnets which holds the sheet brought in contact therewith suspended after it has been released by the suction cups, and then the feeding in fingers may engage the sheet and move it edgewise on the magnets into the machine to be operated upon.

Referring more in detail to the drawings, the cross head 9 is provided as herein shown with two suction cups 15 and 16. As clearly shown in Fig. 2, there are two cross heads 9, 9, two feeding in fingers 10, 10 and two reciprocating rods 11, 11, carrying the fingers. The cross head 9 is mounted on the end of the reciprocating plunger 8 and this reciprocating plunger 8 moves endwise in the supporting bracket 17. Each suction cup as herein shown is formed of rubber and is held on the cross head by a threaded bolt 18 which is formed with a central opening 19 therethrough leading to a chamber 20 in the cross head. The chamber 20 of the cross head may be connected by a passage 21 to a passage 22 which leads to a passage 23 extending lengthwise of the plunger 8 and this passage is connected to a suitable pipe 24 which leads to a suction creating means. Intermediate the passages 21 and 22 there is a valve 25 of the plunger type. Said valve has an annular recess 26 formed therein, and when this valve is in the position shown in Fig. 3, the annular recess 26 is out of register with the passages 21 and 22 and therefore these passages are disconnected. When, however, this plunger is moved endwise to the position shown in Fig. 8, then this annular recess joins the two passages 21 and

22 and thus the suction cup indicated at 16 is subjected to the suction creating means, and if the cup is in contact with the sheet, a vacuum will be created therein which will cause said suction cup to firmly grip and hold the sheet and lift it from the stack when the cross head is moved by the reciprocation of the plunger 8. The suction cup 15 is similar in construction and is held by a threaded bolt 18 which is threaded into a cross head and this bolt is provided with a passage 19 which leads to a chamber 27. The chamber 27 is connected with the passage 28 and this passage 28 may be connected with the passage 22. Said connection is controlled by a valve plunger 25, the annular recess 26 serving to connect these two passages 22 and 28 when the valve plunger is moved to the position shown in Fig. 8. The chamber 20 is also connected to a passage 29 and the passage 29 may be connected with a passage 30 leading to the atmosphere. Said connection is controlled by the valve plunger 31 having an annular recess 32. There is a passage 33 connected with the chamber 27 and this passage also may be connected by this valve plunger to the atmosphere either through the passage 30 or the passage 34. Likewise the passage 29 may be connected to the atmosphere through this passage 34.

From the above it will be apparent that when the cross head is moved to the position shown in Fig. 8, the suction cups will be brought into contact with the topmost sheet in the stack 7 and as the cross head forces the suction cups firmly into contact with the sheet, the rubber cups will yield slightly. The ends of the valve plungers 25 and 31 engage the sheet just a little before the suction cups and as these plungers are moved endwise through the yielding of the suction cups to the pressure of the cross head, the annular recess 26 will be brought into register with the passages 21 and 28 and thus the suction cups will be connected with the suction creating means and a vacuum created in each cup. At this time the plunger 31 is moved sufficient so as to close the connection between the passages 29 and 33 with the atmosphere. The sheet will therefore be firmly gripped and as the cross head moves outwardly the valve plungers remain in the position to which they have been shifted by the sheet, the sheet will be carried by the cross head until it is brought into engagement with the supporting magnets which are indicated at 35. As shown in the drawings, there are four magnets 35. These magnets are of the horse shoe type and are similar in construction. The magnets 35 are carried by a plate 36 which is secured by means of a bolt 37 to a supporting bracket 38, there being a bracket for each magnet. Just as the sheet is being brought into range of the magnets, the valve plungers 25 and 31

31 engage the brackets 17 and are moved endwise so that the annular recess 26 is moved out of register with the passage 22 and therefore the suction cups will be disconnected from the suction creating means. At the same time, by the movement of the plunger 31, the annular recess 32 registers with the passage 29 and thus each suction cup is opened to the atmosphere. This causes the 10 suction cups to release their grip upon the sheet and the sheet will be held suspended by the magnets. The suction cups move just slightly out of range of the sheet so that it may be moved edgewise freely by the feeding 15 in fingers 10, the magnets sustaining the sheet and permitting the edgewise movement thereof.

It will thus be seen that I have provided the means for feeding sheets which has all 20 the advantages of the rubber suction cup for creating and lifting the sheet from the stack, and at the same time, has all the advantages of the metal cups as to free edgewise movement of the sheets, while in contact with the 25 sustaining means.

It is obvious, of course, that minor changes in the details of construction and the arrangement of the parts may be made without departing from the spirit of the 30 invention as set forth in the appended claims.

Having thus described the invention, what I claim as new and desire to secure by Letters-Patent, is:—

35 1. A sheet metal feeding mechanism comprising a yielding suction device for engaging the sheet and separating the same from a stack of sheets, magnetic means for receiving the metal sheets and holding the same suspended after the sheets are released by the suction device, and means for moving the suspended sheets edgewise on said magnetic supporting means.

2. A sheet metal feeding mechanism comprising a reciprocating yielding suction cup for engaging a sheet and separating the same from a stack of sheets, magnets for receiving the metal sheets from the reciprocating suction cup and holding the same suspended after the sheets are released by the suction cup, and means for moving the suspended sheets edgewise on the magnets.

3. A sheet metal feeding mechanism comprising a reciprocating cross head, a plurality of yielding suction cups carried thereby, valves for controlling the connection of the suction cups to a suction creating means, magnets arranged to engage the sheet after it is separated from the stack and for holding the same suspended after the suction means has released the same, and means for moving the sheet endwise on the magnet.

4. A sheet metal feeding mechanism comprising a reciprocating cross head, a yielding suction cup carried thereby, valve mechanism

for connecting said suction cup to a suction creating means or to the atmosphere, said valve mechanism being operated by the sheet to open the suction cup and connect the suction cup to the vacuum creating means, said 70 valve mechanism being operated by the frame of the machine for connecting said suction cup to the atmosphere, magnets for engaging the sheet just prior to the connecting of the suction cup to the atmosphere 75 whereby the sheet will be sustained by the magnets, and means for feeding the sheet edgewise on the magnets.

5. A sheet metal feeding mechanism comprising a reciprocating plunger, a frame supporting the same, a cross head carried by the plunger, a plurality of rubber suction cups carried by the cross head, reciprocating valves mounted in the cross head and adapted to engage the sheet whereby the 80 valves are shifted for closing the suction cups to the atmosphere and for connecting the suction cups to the suction creating means, and means for operating said valves when the sheet has been lifted from the stack 85 for disconnecting said suction cups with the suction creating means and for connecting the same with the atmosphere, a series of magnets arranged to engage the sheets just prior to the releasing of the same by the suction cups for sustaining the sheets, and means for moving the sheets edgewise on the magnets.

6. A sheet metal feeding mechanism comprising a stack holder, a reciprocating plunger, a cross head carried thereby, feeding in fingers, means for reciprocating the same in a direction at right angles to the movement of the plunger, rubber suction cups carried by the cross head, plunger valves mounted in the cross head, passages formed in the cross head controlled by said valves whereby the suction cups may be connected either to a suction creating means or to the atmosphere, said plunger valves being disposed and constructed so that said valves are shifted by the sheet when the suction cups engage the sheet for connecting the suction cups to the suction creating means and disconnecting the same from the atmosphere, and means for engaging said 100 valve plungers for shifting the same after the sheet has been separated from the stack 105 so that the suction cups are disconnected from the vacuum creating means and connected to the atmosphere, a series of magnets arranged so as to engage the sheets just prior to the releasing of the sheet from the suction cups and for holding the sheet suspended in the path of reciprocation of the 110 feeding in fingers whereby the feeding in fingers may move the sheet endwise on the magnets and into the operating machine.

7. A conveyor for magnetic material including a suction member and a magnetic 115 120 125 130

member, said suction member movable from a lower to a higher level and bringing a piece of magnetic material within the effective range of said magnetic member, at an intermediate point in the range of the movement of said suction member, substantially as described.

8. The combination with a suitable support for the sheets, a receiver, and picking means movable toward and from the sheets, of stripping means arranged to strip the sheets from the picking means to sustain the same, and transfer means for transferring the sheets from the stripping means to the receiver.

9. The combination with a suitable means for sustaining metallic sheets, and a receiver, of a picking means movable toward and from the sheets to pick the sheets successively, stripping magnets arranged on opposite sides of the picking means for stripping the sheets from the picking means, and means for shifting the sheets from the stripping magnets to the receiver.

10. In a machine of the class described, the combination of a plurality of suction cups adapted to pneumatically lift a sheet of material, and means disposed in the path of travel of said sheet to release the sheet from said cups during the upstroke of the cups and hold said sheet when released from the cups.

11. In a machine of the class described, the combination of a plurality of reciprocating suction cups adapted to lift a sheet of material, and means disposed in the path of travel of a sheet lifted by the said cups for breaking the seal between said sheet and the cups and holding said sheet when released from said cups.

12. In a machine of the class described, the combination of a sheet lifting device,

means for reciprocating said device, and means disposed in the path of and above a lifted sheet for separating said sheet from said lifting device and holding said sheet in position to be transferred.

13. In a machine of the class described, the combination of reciprocating sheet lifting apparatus, a feed channel, magnets disposed in alignment with said channel and in the path of a sheet lifted by said apparatus for separating said sheet from the lifting apparatus and holding the same in alignment with said channel, and means for transferring said sheet from said magnets into said channel.

14. In a machine of the class described, the combination of sheet lifting apparatus, magnets adapted to engage and hold a lifted sheet, a feed channel, and means for transferring said sheet edgewise across said magnets into said channel.

15. In a machine of the class described, the combination of a magnet, means for bringing a sheet of metal and said magnet into co-operative relation, and means for removing said sheet edgewise from said magnet.

16. In a machine of the class described, the combination of a plurality of magnets, means for disposing a sheet of metal within the magnetic field of said magnets, a feed channel, and means for moving said sheet transversely of the magnets into said channel.

17. In a machine of the class described, the combination of sheet lifting apparatus, a feed channel, transferring mechanism, and stationary means for controlling a sheet lifted by said lifting apparatus during its transfer into said channel.

In testimony whereof I affix my signature.
THOMAS MYHRUM.
